US00D938929S

(12) **United States Design Patent** (10) **Patent No.:** **US D938,929 S**
(45) **Date of Patent:** **** Dec. 21, 2021**

(54) **COMMUNICATION DEVICE**

(71) Applicant: **Motorola Mobility LLC**, Chicago, IL (US)

(72) Inventors: **Poliana Feliconio Pereira**, San Paulo (BR); **Mark Finney**, Chicago, IL (US); **Joel Soto**, Maywood, IL (US)

(73) Assignee: **Motorola Mobility LLC**, Chicago, IL (US)

(**) Term: **15 Years**

(21) Appl. No.: **29/647,086**

(22) Filed: **May 9, 2018**

(51) **LOC (13) Cl. 14-03**

(52) **U.S. Cl.**

USPC ..... **D14/138 AB**

(58) **Field of Classification Search**

USPC ..... D14/315-318, 341-347, 420, 426, 240, D14/129-130, 496, 137, 138 R, 138 AA, D14/138 AB, 138 AC, 138 AD, 138 C, D14/138 G, 147, 203.1-203.8, 218, 247, D14/371, 248, 388-389, 374, 429, 453; D10/104.1, 50, 65; D21/324, 329, 330, D21/332

CPC H04M 1/0214; H04M 1/0218; H04M 1/0216; H04M 1/0227; H04M 1/0247; H04W 88/02

(57) **CLAIM**

The ornamental design for a communication device, as shown and described.

DESCRIPTION

FIG. 1 is a front perspective view of a communication device showing the new design;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown in FIGS. 1-8 that are immediately adjacent to the shaded areas, and define unshaded regions, show portions of the communication device that form no part of the claimed design.

1 Claim, 6 Drawing Sheets
